ELECTRICAL STARTING AND IGNITION
SYSTEM FOR INTERNAL-COMBUSTION
ENGINESRobert E. Slayton, Elmira, N. Y., assignor to Ben-
dix Aviation Corporation, South Bend, Ind., a
corporation of Delaware

Application January 22, 1943, Serial No. 473,238

4 Claims. (Cl. 123—179)

The present invention relates to electrical starting and ignition systems for internal combustion engines and more particularly to an arrangement which is operative in cold weather to delay closure of the ignition circuit of an engine so that the engine is initially cranked with out ignition.

When a very cold internal combustion engine is to be started, it has often been found to be advantageous to crank the engine for a brief period of time prior to closure of the ignition circuit. This insures that all the cylinders will be well charged with a rich fuel mixture before any of them are ignited. It also tends to dilute the oil film on the cylinder walls, which reduces the viscosity of the oil and thereby increases the cranking speed. When the ignition circuit is then closed, the cylinders are all in condition to fire in sequence and sustain the rotation of the engine without interruption. The occurrence of so-called "false starts" requiring repeated operation of the cranking mechanism, is thus obviated.

It is an object of the present invention to provide a novel electrical system for internal combustion engines which is arranged to delay closure of the ignition circuit when the engine is chilled.

It is another object to provide such a device in which the ignition circuit incorporates a thermostatic switch which opens at low temperatures.

It is another object to provide such a device including electrical heating means for the thermostat under the control of the operator.

It is another object to provide such a device including heating means for the thermostat controlled by the ignition switch.

It is a further object to provide such a device including heating means for the thermostat controlled by the starting switch.

It is another object to provide such a device in which the thermostat is warmed by heat from the engine during the operation of the engine.

Further objects and advantages will be apparent from the following description taken in connection with the accompanying drawing in which:

Fig. 1 is a semi-diagrammatic illustration of an electrical system incorporating a preferred embodiment of the invention showing the parts in idle and cold position;

Fig. 2 is a similar view of a second embodiment of the invention in which the thermostatic switch is controlled concurrently with the starting switch; and

Fig. 3 is an enlarged detail of the thermostatic

switch controlling the ignition circuit, the thermostat being shown in its warm condition.

In Fig. 1 of the drawing there is illustrated a starting circuit for an internal combustion engine not illustrated, including a battery 1 grounded at 2 and connected by a lead 3 to a magnetic starting switch 4. Switch 4 is connected by a lead 5 to the starting motor Sm which is grounded at 6 to complete the starting circuit. Switch 4 is provided with an actuating coil 7 grounded at 8 and connected by a lead 9 through a starter control switch 11 to the battery lead 3.

An ignition circuit for the engine is provided comprising an ignition switch 12 connected by a lead 13 to the battery lead 3 and by a lead 14 to a thermostatic snap switch indicated generally by numeral 15. Thermostatic switch 15 is connected by a lead 16 to the primary 17 of the ignition coil 18 which is grounded through timer 19 in the usual manner, the secondary 21 of the coil being connected through distributor 22 to the spark plugs 23 of the engine.

According to the present invention, the thermostatic switch 15 comprises a flexible switch blade 24 anchored at 25 and having at its free end a double contact 26 which is arranged to engage alternatively a contact 27 on the ignition lead 16 or a fixed contact 28 grounded at 29. Thermostatic means for actuating the switch blade 24 is provided in the form of a bi-metallic strip or bar 31 also mounted at one end on the fixed anchorage 25 and having its free end connected to the free end of the switch blade 24 through a spring toggle arrangement so as to 35 constitute a snap action device.

As shown in Fig. 3, this is accomplished by forming the switch blade 24 as a bifurcated member, and mounting the thermostatic strip 31 so that its free end may pass through the space 40 between the furcations of the switch blade. Spring member 32 is then mounted under slight initial compression between the free end of the thermostatic strip and the cross bar 33 of the switch blade. Preferably bearing cups 34 and 35 are employed to form seats for the ends of the spring 32 and constitute rocker bearings with the adjacent surfaces of the thermostatic strip and switch blade.

The thermostatic strip 31 is so mounted and constituted that when its temperature is below a predetermined minimum, such, for example, as 10° F., it will occupy the position illustrated in Fig. 1, and will consequently hold the switch blade 24 in position to cause the contact 26 to engage the grounded contact 28. When the strip

is heated substantially above this minimum point, however, it will bend upward, moving the connected end of the toggle spring 32 with it, compressing said spring until the dead center position is reached, after which expansion of the spring will snap the contact 26 away from the grounded contact 28 and into engagement with the ignition contact 27, as illustrated in Fig. 3.

Means under the control of the ignition switch 12 for heating the thermostatic strip 31 to cause closure of the ignition circuit after a predetermined time is provided in the form of a heater coil 36 connected at one end to the ignition circuit lead 14 and at the other end by a lead 37 to the anchored end of the switch blade 24. The coil 36 has a comparatively low resistance and is so designed that when it is grounded through contacts 26, 28, it will heat up rapidly and cause the thermostatic strip 31 to open contacts 26, 28, and close the ignition circuit contacts 26, 27 after a few seconds. The resistance of the heater coil is so low that it does not affect the operation of the ignition system, the slight amount of heat generated by the coil during the operation of the engine being merely sufficient to keep the thermostatic strip slightly warm.

In the operation of this embodiment of the invention, when the engine is chilled so that the thermostatic contacts are in the positions illustrated in Fig. 1, closure of the starter control switch 11 and the ignition switch 12 by the operator causes the magnetic starting switch 4 to close, and at the same time completes the heating circuit through coil 36 and contacts 26, 28. The engine is thereupon cranked for a few revolutions while the ignition circuit is held open by the thermostatic switch 15. After a few seconds, the thermostatic strip 31 is sufficiently heated by the coil 36 to bend up, moving the toggle spring 32 past its dead center position so that it snaps the switch blade 24 down and closes contacts 26, 27, completing the ignition circuit. Since all the cylinders of the engine are by this time charged with a rich fuel mixture, self-operation of the engine in a continuous and reliable manner is immediately obtained.

The embodiment of the invention illustrated in Fig. 2 is generally similar to that shown in Fig. 1, and the parts thereof are similarly numbered. In this embodiment, however, the heating of the thermostat is controlled by the starter control switch instead of the ignition switch, and the temperature of the thermostatic switch is maintained by heat conduction from the engine during the operation thereof. For this purpose the thermostatic switch 15' is mounted on the engine exhaust manifold 38, and the heater coil 36' is connected at one end by a lead 39 to the starting switch coil lead 9. The other end of the heater coil 36' is grounded as indicated at 41 to complete the heating circuit. The ignition lead 14 is connected directly to the switch blade 24 to complete the ignition circuit through contacts 26, 27 to the ignition coil 18.

In the operation of this embodiment of the invention, when the temperature of the parts is below the established minimum the thermostatic switch 15' will be in the position illustrated, with the ignition contacts 26, 27 open. Closure of the ignition switch 12 by the operator accordingly has no immediate effect. Closure of the starting control switch 11 by the operator simultaneously energizes the magnetic starting switch coil 7 and the thermostat heating coil 36' thus causing the starting motor to crank the engine, and after a predetermined time interval causing the thermostatic switch to close the contacts 26, 27 and complete the ignition circuit, whereby the engine is rendered self-operative. When the starter control switch 11 is opened by the operator, the heating coil 36' is de-energized, but the temperature of the thermostatic strip 31 is maintained sufficiently high to prevent opening the ignition contacts 26, 27 by heat conducted from the engine.

Although but two embodiments of the invention have been shown and described in detail, it will be understood that other embodiments are possible and various changes may be made in the design and arrangement of the parts without departing from the spirit of the invention as defined in the claims appended hereto.

What is claimed is:

1. In an electrical system for internal combustion engines an ignition circuit including an ignition coil and a switch for controlling the energization of the coil, thermostatic means for opening the switch at a predetermined low temperature and manually controlled electrical heating means for the thermostatic means.
2. In an electrical system for internal combustion engines an ignition circuit including an ignition coil, and means for controlling the energization thereof including a manually operable ignition switch and a thermostatic switch arranged to be opened at a predetermined low temperature, and electrical heating means for the thermostat controlled by said ignition switch.
3. In an electrical system for internal combustion engines an ignition circuit including an ignition coil and means for controlling the energization thereof including a switch, thermostatic means for opening the switch at a predetermined low temperature, a starting system for the engine including a starter control switch and heating means for the thermostat controlled by said starter control switch.
4. In an electrical system for internal combustion engines a snap switch having two sets of contacts arranged to be closed alternatively, thermostatic controlling means for the switch, an ignition circuit for the engine including one of said sets of contacts and a heating circuit for the thermostat including the other set of contacts, the heating circuit contacts being closed when the thermostat is chilled, and the ignition circuit contacts being closed when the thermostat is warm.

ROBERT E. SLAYTON.
